(57) **CLAIM**

The ornamental design for a jacket with partially attached vest, as shown and described.

DESCRIPTION

FIG. 1 is a front elevational view of a jacket with a vest hidden in a back pocket;

FIG. 2 is a rear elevational view of the jacket with the vest hidden in the back pocket;

FIG. 3 is a side elevational view of the jacket with the vest hidden in the back pocket;

FIG. 4 is a side elevational view, opposite that of FIG. 3, with the vest hidden in the back pocket;

FIG. 5 is a front elevational view showing the vest in an exposed configuration on an exterior of the jacket;

FIG. 6 is a rear elevational view showing the vest in an exposed configuration on the exterior of the jacket;

FIG. 7 is a side elevational view showing the vest in an exposed configuration on the exterior of the jacket; and,

FIG. 8 is a side elevational view, opposite that of FIG. 7, showing the vest in an exposed configuration on the exterior of the jacket.

The broken line illustration symbolizing stitching as well as the remainder of the broken lines on the surface of the jacket and vest, illustrate portions of the design that form no part of the claim.
